CLAUDIUS UGNON, JERRY GALOPPA, AND CHARLES SALDARINI, OF PATERSON, NEW JERSEY, ASSIGNEES TO RIVERSIDE ENGINEERING CO. INC., OF PATERSON, NEW JERSEY, A CORPORATION OF NEW JERSEY.

MANGLE OR QUETCH.

Application filed June 14, 1921. Serial No. 477,423.

To all whom it may concern:

Be it known that we, CLAUDIUS UGNON, JERRY GALOPPA, and CHARLES SALDARINI, a citizen of the Republic of France, a citizen 5 of the United States and a subject of the King of Italy, respectively, residing at Paterson, in the county of Passaic and State of New Jersey, have invented certain new and useful Improvements in Mangles or 10 Quetches, of which the following is a specification.

This invention relates to machines, known as "mangles" or "quetches," in which fabrics are treated with liquid substances, as 15 size, by passing the fabric between rollers one of which rotates partly submerged in a bath of or otherwise is made to receive the liquid. Where there are only two rollers the fabric takes up too much of the liquid, and 20 where, as is usually the case, there are three rollers, the lower one taking the liquid from the bath and delivering it to the intermediate roller and the latter delivering it to the fabric squeezed between it and the top roller, 25 the fabric takes up too little of the liquid. Our object is to provide a mangle or quetch so constructed that the fabric can be made to take up just the right quantity of liquid, this being made possible partially by providing but two main rollers, between which the fabric is squeezed and one of which conveys the liquid to the fabric, and in addition a rolling squeegee or squeegee roller which bears on this liquid-conveying roller and so 30 limits the amount of liquid to be carried by the latter roller to the fabric; in the preferred construction the squeegee roller is carried by a lever having means to adjust the pressure of said roller on the liquid-conveying roller and so vary at the will of the operator the amount of liquid allowed to pass to the fabric. A further object is to provide simple and efficient and easily operated means for moving one of the main rollers 35 40 45 50 toward and from the other, whereby the rollers may be made to occupy the "open" relation—so as to admit the fabric and also avoid their standing in a condition of mutual pressure when the machine is idle—the mutually contacting relation, desirable in preliminarily adjusting the fabric between them, and the pressure relation. A still further object is to provide for the withdrawal

of the squeegee roller from the liquid-carrying roller when the two main rollers are in 55 the "open" relation.

The drawing shows a side elevation of the improved machine.

In the frame *a* is journaled a horizontal drive shaft *b* which, through suitable gearing, drives a vertical shaft *c*, said gearing in the present case being variable speed-gearing and including a face plate *d* on shaft *b* and a friction wheel *e* splined on and hence shiftable longitudinally of shaft *c* and radially of the face plate; *f* designates a well-known mechanism for so shifting the friction wheel. Shaft *c* is connected by gearing *g* with a horizontal shaft *h* journaled in the frame. 60 65 70

Journaled in the frame is a horizontal shaft *i* on which is fixed a roller *j* which dips in a bath of the liquid of treatment contained in a receptacle *k*; shaft *i* has fixed thereon a gear *l* which meshes with a gear *m* fixed on shaft *h*. Thus when shaft *c* is driven roller *j* will be rotated, the direction of rotation being indicated by the arrow. 75

In the frame, on an axis *n* parallel with shaft *i*, is fulcrumed a lever *o* which extends over the roller *j*. Also in the frame and on an axis *p* below and parallel with axis *n* is fulcrumed a lever *q*. In the lever *o* is journaled, on a horizontal axis *r*, a roller *s* arranged vertically above the roller *j* and adapted to bear down upon the fabric *A* interposed between them. In the lever *q* is journaled the squeegee roller *t* which bears against the roller *j* between the point at which it receives liquid from the receptacle *k* and the line of pressure between rollers *j* and *s* and at such a position that the liquid taken upon the periphery of roller *j* will reach the squeegee roller *t* before it reaches the fabric. (It will be understood that there are in fact two levers *o* and two levers *q*, one at each side of the machine, so that both ends of the rollers *s* and *t* are supported). On the lever *q* and adjustable thereon toward and from its fulcrum is a suitable weight support *u* carrying a weight or weights *v*. On shifting the weight support toward and from the fulcrum of lever *q* the pressure of the squeegee roller on roller *j* will be varied, thus to vary the quantity of liquid allowed to pass said roller on its way to the fabric. 80 85 90 95 100 105

By providing the two pressure rollers j s and a squeegee roller which contacts with the periphery of the liquid conveying roller (j), and especially by providing for adjusting the pressure of the squeegee roller against the liquid conveying roller, as the means u v , it is possible to supply to the fabric precisely that amount of liquid which under the circumstances it requires, and never more nor less.

It will be understood that the fabric to be treated is made to pass between the rollers j s in any well known way, as by being delivered from a supply beam B and wound on a take-up beam C , which latter is driven by any suitable means (not shown).

In these machines it is necessary to provide means for spacing the rollers j s in order to enter the fabric between them and for exerting pressure on one toward the other so that while rotating the fabric will be squeezed or pressed between them; it is also desirable that this means should be of such a character that, where the roller which is movable toward and from the other is above the latter as in the present case, said means may assume a position where the weight of the levers and other parts is alone effective to exert pressure on the fabric, as when the rollers are being rotated for the purpose of entering the fabric between them preliminarily. We have devised the following improved means for these purposes.

On an axis w at the front of the machine is fulcrumed a weighted lever x projecting under it. This lever has pivotally connected to it a link y in the upper end of which a shaft z is journaled. This shaft forms the fulcrum of a lever including the shaft a short lever arm 3 and a long lever arm 4 which forms an operating handle, the lever arms 3 and 4 being fixed on the shaft. There is a link connecting the end of lever 3 with the lever o . This link includes three parts, an upper part 5 pivoted to lever o , a lower part 6 having its lower end bent rearwardly and back to lever arm 3 and a turnbuckle 7 threaded onto the ends of parts 5 and 6 and affording means to vary the length of the link. Another link 8 pivotally connects the shaft z with a part of the frame. (It may be remarked that the following parts are duplicated there being one at each side of the machine, to wit: x , y , 3 , 5 , 6 , 7 , and 8). The means x — y — 8 affords a purchase for lever 4 — z — 3 when the latter is moved to the full-line position, whereby to act through link 5 — 6 — 7 to lift lever o and hence elevate roller s clear of roller j , said means then having its downward movement limited by a stop 9 . Said means on the other hand acts as a load to exert the desired pressure on roller s toward roller j , when, lever 4 — z — 3 having been moved to the position indicated by the dotted outline of arm 4 , said lever is moved

downward from that position, the said lever then having a purchase on the lower end of link 5 — 6 — 7 and acting to raise said means. In the intermediate position of the lever—where 4 is shown dotted—the said means has come to rest at x' and roller s rests on roller j subject to the action of gravity on only itself and the parts connecting it with 3 . In short, between the pressure exerting means (normally moved in a direction away from the roller but having its movement in that direction limited) and the roller s there is a power-transmitting train including a lever (4 — z — 3) and separate connections respectively connecting different points of the lever with the roller s and said means, these connections being in the present case the links 5 — 6 — 7 and y .

At each extreme limit of its motion the axis of pivotal connection between link 5 — 6 — 7 and 3 passes a straight line connecting the axis of z and the axis of pivotal connection between 5 — 6 — 7 and o (the lever and said link forming, therefore, a toggle connection between lever o and the means or load x — y — 8) and so the entire system of parts will become locked at either extreme of movement so that it cannot return without turning back lever 4 — z — 3 .

The rollers j and s , and particularly the former, are usually surfaced with some relatively soft material, as rubber. When the machine is not in use it is therefore desirable to separate the rollers. To accomplish this as between the rollers j and t there is provided a link 10 which is pivoted to one of these levers and has a longitudinal slot 11 receiving a pin 12 on the other, the slot allowing slight pressure movement of lever o after both rollers have contacted with roller j .

Having thus fully described our invention, what we claim as new and desire to secure by Letters Patent is:

1. A machine for treating fabrics with liquid including, in combination, a supporting structure, three members two of which are coacting, fabric-pressing rolling members and the third of which is a squeegee member which bears against one of the first two members, and means to supply the liquid of treatment to the periphery of one of the first two members, said structure having means to separate the first two members and at the same time the squeegee member and the member against which it bears.

2. A machine for treating fabrics with liquid including, in combination, a frame, two coacting fabric-pressing rollers, one journaled in the frame and the other being movable toward and from the first roller, means to supply the liquid of treatment to said first roller, a squeegee movable into and out of contact with the first roller, and means, affording support for said other

roller and the squeegee, movable to shift them both away from the first roller at the same time.

3. A machine for treating fabrics by pressure including, in combination, a frame, two coacting fabric-pressing rollers, one journaled in the frame and the other being movable toward and from the first roller, a pressure exerting means between which and the movable roller the first roller is arranged, said means being normally moved in a direction away from said rollers but having its movement in that direction limited, and a power-transmitting train connecting the movable roller and said means and including a lever and separate connections respectively connecting different points of said lever with the movable roller and said means.

4. A machine for treating fabrics by pressure including, in combination, a frame, two coacting fabric-pressing rollers, one journaled in the frame and the other being arranged above and movable toward and from the first roller, a gravity-depressed pressure exerting means below the first roller having its downward movement limited, and a power-transmitting train connecting the movable roller and said means and including a lever and separate connections respectively connecting different points of said lever with the movable roller and said means.

In testimony whereof we affix our signatures.

CLAUDIUS UGNON.
